DESIGN FOR A WALL BRACKET LAMP

Edward Kanter, Cleveland Heights, Ohio

Application August 27, 1934, Serial No. 53,079

Term of patent 3½ years

To all whom it may concern:

Be it known that I, EDWARD KANTER, a citizen of the United States, residing at Cleveland Heights, in the county of Cuyahoga, and State of Ohio, have invented a new, original, and ornamental Design for a Wall Bracket Lamp, of which the following is a specification, reference being had to the accompanying drawing, forming part

thereof, wherein Fig. 1 is a perspective view and Fig. 2 a view in side elevation of a lamp showing my new design.

I claim:

The ornamental design for a wall bracket lamp, substantially as shown.

EDWARD KANTER.
